UNITED STATES PATENT OFFICE

HENRY H. YERK AND WILLIAM J. BAUMBERGER, OF DAVENPORT, IOWA, ASSIGNEES
TO MICRO MACHINE COMPANY, OF BETTENDORF, IOWA, A CORPORATION OF IOWA

GRINDING MACHINE

Application filed November 5, 1925. Serial No. 67,185. Renewed July 8, 1929.

This invention relates to grinding machines, and more particularly to duplex grinders in which grinding wheel spindles are rotated about their axes and also orbitally about other axes eccentric to the spindles.

To finish a bore in work which must be ground from opposite ends by a single grinding wheel, the work must be set up independently for each operation, or the fixture carrying the work must be adjusted. This condition is also present when a single grinding wheel is employed to finish separate sections of work which are to be assembled with their finished bores in alignment. Considerable time is consumed to accurately position the work in order that the ends of the bores to be finished will be presented in the same manner to a single grinding wheel. Additional time is required when the bores to be finished are of different diameters at opposite ends, as it is necessary to change the grinding wheel.

The element of time is materially lessened by the use of oppositely disposed grinding elements and it is an object of this invention to feed both grinding elements individually or simultaneously with respect to a stationary fixed piece of work in which the bores are finished from opposite ends, and thereby reduce the time required for such operation to a minimum.

Another object of our invention is to provide a duplex grinding machine in which opposed spindles can be reciprocated individually or simultaneously either by power or manually, while they are rotating axially and orbitally.

Another object of our invention is to provide a work supporting table for a grinding machine which can be readily adjusted in a vertical plane to accurately position work relative to a grinding wheel.

These and other objects will appear in the following specification.

In the accompanying drawings, which illustrate an embodiment of our invention:

Figure 1 is a front elevation of a grinding machine.

Fig. 2 is a vertical section, partly in elevation, on line 2-2 of Fig. 5.

Fig. 3 is a rear elevation of the machine.

Fig. 3A is a sectional view of a speed changing device.

Fig. 4 is a front elevation, partly in section.

Fig. 5 is a sectional plan view of the machine on line 5-5 of Fig. 1; and

Fig. 6 is a vertical section on line 6-6 of Fig. 1.

Referring to the drawings by characters of reference, A represents the frame of a grinding machine upon which a work supporting table B and a pair of spindle supporting frames C and D are supported. Headstocks E are secured upon the top of the frames C and D. It will be observed that the work supporting table is relatively stationary and that the spindle supporting frames C and D carrying the headstocks E are reciprocable upon the machine frame to finish the bores of work F held upon the stationary table B.

The work support B comprises a supporting bracket 12 (Fig. 6) which carries a guide 11 on which the work table 10 is adjustable transversely. The supporting bracket 12 is located in spaced relation to the rear wall of the machine frame. The bracket 12 is provided on its inner wall with a boss 13 having a vertically extending aperture in which a cylindrical bearing member 14 is secured. The machine frame is provided with bearings 15 in which the screw shaft 16 is rotatably supported and the shaft is screwed through the inner threaded wall of the bearing 14. A bevel gear 17 is secured to the upper end of the screw shaft and by rotating such shaft in its bearings the work supporting table can be raised or lowered to place the work carried thereon in desired vertical relation with the grinding wheels. A shaft 18 extends transversely across the machine frame and has secured to one end thereof a bevel gear 19 which meshes with the gear 17. The other end of the shaft 18 projects from the front wall of the machine frame 95 and is formed to receive a crank for manually rotating the same, suitable means 20 being provided to indicate the elevation of the table relative to the axes of the grinding wheels. The transverse adjustment of the 100

fixture 10 and the vertical elevation of the supporting table permit the work F, secured on the fixture, to be readily and accurately positioned relative to the grinding wheels.

5 A spindle carried in spindle housing 21 extends from the inner end of each of the headstocks E, and suitable mechanism is provided in the headstocks to cause the spindles to rotate about their own axes, and also to rotate bodily in an orbital path about axes eccentric to the spindles. The opposed ends of the spindles carry grinding wheels 22 which, as shown, are of different sizes to finish the bores in the work F which are of different 10 diameters. One type of mounting and driving mechanism for the spindles above referred to is fully described in the pending application for patent, Serial No. 730,626, filed 15 August 7, 1924.

20 The headstocks and their supporting frames D and C are reciprocated upon the bed of the machine, and the sides 23 of the supporting frames extend below the top of the machine frame. The adjacent walls of the 25 frame sides and the side walls of the machine frame are beveled complementary to maintain the frames in a uniform horizontal plane in any position of the reciprocal movement of the frames. It will be seen that the mechanisms for axially rotating the spindles are 30 movable with the housings D and C so that power can be transmitted in any position the housings may be moved.

A bracket 24 (Fig. 4) depends from the inner 35 end of each of the headstock supporting frames C and D and projects interiorly of the machine frame. A motor 25 is secured upon each of the brackets 24 and a shaft 26 extends, longitudinally of the machine, from each of the outer ends of the motors, and the shafts 26 are rotated thereby. These shafts 26 are formed in sections and the adjoining ends of the sections are connected by universal 40 and telescoping joints 27 to permit movement 45 of the spindle rotating mechanisms. A pulley 28 is secured to the outer ends of these shafts and transmits power to pulleys 29 by means of the belt 30. The pulleys 29 drive the mechanism for rotating the spindles 50 about their axes. It will be seen that the mechanisms for axially rotating the spindles are movable with the headstocks when they are reciprocated, and are independent of the other driving mechanism for reciprocating 55 the headstocks and for rotating the spindles in an orbital path.

A main driving motor 33 (Fig. 5) is secured adjacent to the rear of the machine frame, and power is transmitted from a pulley 34 thereon by a belt 35 which extends around a pulley 36 carried by a stub shaft 37 secured to the rear wall of the machine frame by bearing bracket 38. The stub shaft 37 has a pinion 39 secured thereto which meshes with 60 a pinion 40 secured upon a shaft 41 which is

rotatably secured in bearings 42 and 43. A cone pulley 44 is secured upon the shaft 41 intermediate the bearings 42 and 43, and another cone pulley 45 is secured upon a shaft 46 which is parallel to shaft 41 and is carried 70 by the bearings 47 and 48. The cone pulleys are of a similar shape, being positioned reversely relatively so that their peripheries are parallel and slightly spaced. A belt 49 (Figs. 3 and 3A) extends around the lower cone pulley 45. The cone pulleys 44 and 45 are so positioned in relation to each other that the belt 49 in passing between them engages both cone pulleys frictionally. The upper cone pulley 44 which is driven at a constant 80 speed from the motor 33 as above described thus drives the lower cone pulley by frictional contact through the belt 49 at a speed dependent upon the relative diameters of the cone pulleys where the belt 49 passes between 85 them.

The lower cone pulley 45 transmits the power for actuating the table reciprocating mechanism and the mechanism for rotating the spindles in an orbital path about axes eccentric to the spindles. It will therefore be seen that such mechanisms are driven at a rate of speed which will remain constant for any particular setting of the belt 49 but which may be varied at will by the operator. 90 A yoke 50 is arranged to straddle the belt 49 and is slideable longitudinally of the cones on a rod which is secured in suitable bearings, and by shifting the belt through means of the yoke, the speed of the lower driven cone 45 100 can be varied relative to the constant speed at which the cone 44 is driven from the motor. Thus the speed of movement of the reciprocation of the headstocks and that of the orbital rotation of the spindles can be varied as desired to finish bores of varying diameters so that correct speeds to give the best grinding 105 results can be obtained.

The variable speed driven cone 45, which drives the mechanism for rotating the spindles in an orbital path, also drives the mechanism for reciprocating the headstocks, thus keeping a proper relation between the headstock travel and the revolutions per minute of the orbital movement of the spindles. 110 Such arrangement simplifies the operator's problem as he does not have to adjust the timing of such movements separately. For example, should the headstocks be set to advance .05 inch per orbital revolution of the 115 spindles, they will continue to advance .05 inch per orbital revolution of the spindles, even though the speed of orbital movement be diminished or increased. The maintenance of this relation of the two drives utilizes the full capacity of the grinding wheels without the possibility of overtaxing them, as a correct relation of the speeds of headstock travel and orbital spindle rotation must be maintained to remove a maximum amount of 120 130

stock and to eliminate grinding wheel break-down or grinding wheel glazing.

Mechanism is associated with the belt shifting yoke 50 so that it can be actuated from the front of the machine and with a definite knowledge of the position of the belt between the cones necessary to cause a definite speed of rotation of the driver cone. A cable 51 (Fig. 3) is secured at its ends to the yoke and extends around a pulley 52 from which it passes around pulleys 53 and 54 and then over the pulleys 55 on the shaft 56. The cable passes from the pulleys 55 transversely through the machine frame and over pulleys 57 and around a drum 58 (Figs. 2 and 5) secured on a shaft which extends through the front wall of the frame. A dial 59 is secured to the front of the machine frame and a pointer 60 is secured to the shaft on which the drum 58 is secured. By moving the pointer the cable will be moved, thus shifting the yoke belt shifter, and the relation of the pointer to the dial will permit the cable to be positioned to cause the lower driving cone 45 to rotate at definite speeds, such mechanism being operable by the operator at the front of the machine.

The mechanism for driving the spindles in an orbital path is actuated from the cone pulley 45. A gear 61 is arranged on an end of shaft 46 to mesh with a pinion 62. The gear 61 is driven or remains idle upon operation of the clutch 63. The pinion 62 is secured to a shaft 64 carried at the rear of the machine 30 in the bearings 48 and 65, and a pulley 66 is secured to the end thereof which projects beyond the end of the machine. A pulley 67 is slidably keyed to the shaft 64, and a belt 68 extends therefrom around a pulley 69 35 which is mounted upon a shaft for transmitting power to operate the mechanism for rotating the grinding wheel spindle in an orbital path. A bracket 70 depends from the headstock and is reciprocable therewith, the 40 lower portion of such bracket having a bearing 71 with which the pulley 67 is rotatably connected so that they can reciprocate together longitudinally of the shaft 64. The 45

The other end of the shaft 46 is provided with a pinion 72 which meshes with a pinion 73 on a countershaft 74. A sliding clutch 75 is mounted upon the shaft 46. The pinion 72 is driven or remains idle upon operation of clutch 75. The countershaft 74 is carried in bearings 74^a and 74^b. A pulley 76 is slidably keyed to the shaft 74 and a belt 77 transmits power from pulley 76 to pulley 78 mounted upon a shaft 130 (Fig. 2), connected to the mechanism for rotating in an orbital path the grinding wheel spindle of the headstock E. A bracket 79 (Fig. 3) is secured to the headstock supporting frame C and is provided at its lower end with the bearing 80 in which the hub of the pulley 76 is rotatably mounted. As the headstock reciprocates the

pulley 76 moves along the shaft 74 in unison. As indicated in Fig. 2, the pulley 78 is keyed to the shaft 130 which carries gear 131 enclosed in the housing 133 (Fig. 3). Gear 131 meshes with gear 132 enclosed in the housing 134 and serves to rotate the grinding wheel spindle in an orbital path. 70

It will be seen that the power from the pulley 45 is transmitted to either headstock when the clutches 75 and 63 are engaged, and that each clutch may be engaged or disengaged at will by the operator by means of levers 86 (Fig. 1) whereby the headstocks can be reciprocated independently of each other or together.

The ends of the countershafts 64 and 74 project beyond the ends of the machine frame, and pulleys 66 are secured to the ends thereof. Countershafts 81 extend along the front of the machine adjacent the ends thereof and are geared to reverse gear mechanism contained in the casings 82. The reverse gear mechanism is fully described in U. S. Patent No. 1,633,060, issued June 21, 1927, to William J. Baumberger. Pulleys 83 are secured on the outer ends of the shafts 81, and power is transmitted thereto from the pulleys 66 by the belts 84.

Link mechanisms 85 are associated with the clutches 75 and 63 and are connected to the levers 86 at the front of the machine so that the operator can readily control them. The reciprocation of the headstocks is controlled by the stop mechanism 87 (Fig. 1). Associated with mechanism 87 are adjustable stops 87^a and 87^b which engage a lever 88 when the headstock reaches either end of its stroke. Levers 88 cooperate with the reverse gear mechanism to cause the headstock frame to change its direction of longitudinal movement. The stop mechanism is adjustable to permit various lengths of reciprocable travel of the headstock. Such stop mechanism is well known in the art to which this invention applies.

Power from the gearing in the reverse gear casings 82 is transmitted through the bevel gears 89 (Fig. 5) which mesh with bevel gears 90 on the shafts 91 extending adjacent the inside of the front wall of the machine frame. Gears 92 are secured upon the ends of the shafts 91 and mesh with gears 93 on the shafts 94 which extend inside of the end walls of the machine. Gears 95 are secured on the rear ends of shafts 94 and mesh with gears 96 secured to the ends of shafts 97 exteriorly of the rear wall of the machine. The shafts 97 extend into boxes 98 within each of which change speed gearing of conventional design is carried. The change speed gearing boxes 98 are secured to the rear wall of the machine frame and power is transmitted therefrom by shafts 99 to worms 100 in mesh with worm gears 101 on shafts 102 which extend interiorly of the machine frame and carry gears 130

103 which mesh with racks 104 secured to depending portions of the headstock frames D and C. Worms 100 and worm gears 101 are enclosed in gear housings 101^a.

5 The mechanisms in reverse gear boxes 82 are driven from the driving cone 45 by means of shafts 81. By means of shafts 81, pulleys 83, belts 84, and pulleys 66, connection is made with shafts 64 and 74, respectively. 10 These shafts 64 and 74 are driven from the cone pulley 45, as previously described. The reverse gear mechanisms in the boxes 82 drive gears 103 through the change speed gearing, as above described.

15 It will be seen that the stop mechanism 87 operates to cause the reverse gearing to rotate the pinion 103 first in one direction and then the other, and that the pinions 103 reciprocate the racks 104 and the headstock frames C and D. The work is held stationary on the work table 10, while the headstocks reciprocate, carrying the grinding wheels 22 back and forth over the surfaces being ground. The headstocks and their associated 20 grinding wheels 22 can be reciprocated either simultaneously or individually.

25 It will be observed that the mechanism for axially rotating the spindles is carried with the headstock frames (Fig. 4), and that the mechanisms for driving the mechanism for orbitally rotating the spindles have a sliding driving connection (Fig. 3) to permit their operation when the spindles are reciprocated with the headstocks. By adjusting the belt 30 longitudinally of the cones 44 and 45 the headstock mechanism can be driven at any desired speed within limited ranges.

35 When the change speed gears in the casings 98 are thrown out of driving relation, hand 40 operated mechanism can be utilized to reciprocate the headstocks C and D. Shafts 105 (Fig. 2) extend transversely within the machine frame and project through the front wall thereof, and have hand wheels 106 (Figs. 2 and 5) secured thereto. The shafts 45 105 are carried by the bearings 107 and gears 108 are secured to the inner ends thereof and mesh with the gears 103 which engage the racks 104.

50 A clutch 109 is arranged in association with each power driven shaft 102 to connect or disconnect the pinions 103 from driving relation therewith. Such clutches are operated by link mechanisms 110 which are operated by the rods 111 which extend through 55 the shafts 105 and terminate in buttons 112 exteriorly of the hand wheels 106. By pushing the buttons 112 in or pulling them out, the clutches will operate to disconnect or 60 connect the gears 103 relative to the shafts 102. When the clutches disengage the power driven mechanism from the pinions 103, the operator can rotate either of the hand wheels 106 to reciprocate the associated 65 headstock through the gears 108 and 103.

In order to overcome inequalities in the surfaces being ground, due to varying tension in each belt 30, a pantograph mechanism 115 is used. This mechanism is fully described in the pending application for 70 patent, Serial No. 730,626, filed August 7, 1924, mentioned above. Weights 116 (Fig. 4) pivoted on arms at 117 serve to counter-balance the weight of the pantograph mechanism 115. 75

In Figs. 3 and 5 is shown a water supply system for supplying cooling water to the grinding wheels 22. A rotary pump 118 driven from shaft 41 by the belt 119 draws water by suction through the pipe 120 from 80 the tank 121 and discharges it into pipe 122. Pipe 122 branches at the T 123 and supplies water to the flexible hose pipes 124 which lead into the interior of the headstock and connect with other flexible hose pipes 85 125. Hose pipes 125 connect through suitable couplings to the ends of the spindles carried in spindle housings 21, which spindles are hollow and provided with suitable openings at the ends thereof where the grinding 90 wheels 22 are attached.

With the above described mechanism, work can be positioned upon the machine, and bores can be finished from opposite ends simultaneously or individually. The headstocks carrying the grinding wheels can be reciprocated either by power or by hand, and when driven by power the speed ratio of the reciprocating movement of the headstocks and the orbital movement of the spindles 95 100 will be maintained at a definite speed ratio, as they are driven from the cone 45 and such ratio of movement will not be changed when the speed of rotation of the cone 45 is changed by shifting the belt 49, and in this manner the proper relation of the headstock movement and the speed of orbital movement of the spindles is maintained to give the best grinding results. It will thus be noted that this machine materially speeds 105 up the time required to finish bores from opposite ends. 110

It will be seen, however, that we have provided means for changing the ratios of the speeds of the table travel and spindle movements to suit the grinding machine to obtain the best results under various conditions. Such change of the ratio of speed is of course independent of the relationship between the table travel and the bodily movement of the spindle, wherein the latter increases or decreases in speed when the former increases or decreases in speed. This latter relationship arises from the arrangement whereby the mechanism causing the bodily orbital movement of the spindle and the mechanism for causing longitudinal movement of the table are driven from the same cone pulley, and the rate of rotation of the cone pulley may be varied within relatively 115 120 125 130

small amounts over a relatively wide range by the operator by means of the belt shifting mechanism associated with the cone pulley mechanism as previously explained.

5 It will thus be seen that we have designed a machine in which oppositely disposed spindles have their axes in the same plane and that work with oppositely disposed bores can be ground simultaneously or individually as desired.

10 The bores preferably should be of the same diameter, as the orbital movement of the spindles is controlled by a common change speed mechanism. However, if a quantity 15 of work is to be ground with holes of different diameters, the speed of orbital movement of one spindle could be changed by changing the gearing on one side of the machine to make it slower or faster. The 20 orbital movement then would be the correct one for the bores being ground. Of course, it will be seen that if it is desired to grind a number of castings with oppositely disposed bores not in alignment, the headstocks and 25 spindles could be originally positioned to take care of such castings having bores out of alignment. In this case the spindles may be in different parallel planes, that is offset either laterally or vertically to take care of 30 the bores. One could make the spindles so spaced in parallel axial relation that both of the small holes could be ground simultaneously with grinding wheels of the same size, and both large holes could be ground 35 simultaneously, it being understood that the work is shifted between such operations.

40 Various changes can be made in the details of the construction described herein without departing from the spirit of our invention and the scope of the appended claims.

What we claim is:

1. In a grinding machine, in combination, 45 a base, a vertically adjustable bracket disposed at the rear side of said base, said bracket extending over the top of said base and in spaced relation thereto, a work table mounted on said overhanging bracket portion and adjustable transversely of said base, a pair of headstocks mounted on the top of 50 said base and slidable longitudinally thereof and beneath said work table, said headstocks each having a grinding wheel spindle extending outwardly toward the opposed headstock, independent power units carried by 55 each headstock for rotating said spindles on their respective axes, means operated from a common source of power for rotating said spindles in orbital paths about axes eccentric to their own, and means operated from 60 the same last-mentioned source of power for reciprocating said headstocks longitudinally of said base.

2. In a grinding machine, in combination, 65 a substantially open-top base, a work supporting table disposed substantially cen-

trally of said base, said table being adjustable transversely of said base and vertically, a pair of opposed headstocks mounted on said base and slidable longitudinally thereof, said headstocks carrying grinding wheel 70 spindles each extending outwardly toward the opposed headstock, said spindles being rotatable about their own axes and about axes eccentric to their own, said headstocks extending downwardly into said hollow base 75 and each carrying within said base a motor, means operatively connected to said motor for rotating said spindles at relatively high speeds about their own axes at any adjusted positions of said spindles within said headstocks, and means driven from a common source of power for rotating said spindles about axes eccentric to their own and for reciprocating said headstocks longitudinally 80 of said base.

3. In a grinding machine, in combination, 85 a base, a transversely and vertically adjustable work supporting table carried by said base and disposed substantially midway thereof, a pair of oppositely disposed headstocks mounted on said base and slidable longitudinally thereof, grinding wheel spindles carried by each headstock extending toward the opposed headstock, independent means carried by each headstock for rotating said grinding wheel spindles respectively on their own axes, a longitudinally extending shaft disposed adjacent one of said headstocks, a pulley mounted on said shaft in keyed relation thereto and movable longitudinally thereof, a bracket carried by said headstock, said pulley being secured to said bracket, means for reciprocating said headstocks longitudinally of said base, means for 90 rotating said shaft, and driving means associated with said pulley and adjacent headstock whereby the grinding wheel spindle on said headstock may be rotated in an orbital path about an axis eccentric to its own during the reciprocation of said headstocks. 95

4. In a grinding machine, in combination, 100 a base, a transversely and vertically adjustable work supporting table carried by said base and disposed substantially midway thereof, a pair of oppositely disposed headstocks mounted on said base and slidable longitudinally thereof, grinding wheel spindles carried by each headstock extending toward the opposed headstock, independent means carried by each headstock for rotating 105 said grinding wheel spindles respectively on their own axes, a longitudinally extending shaft disposed adjacent each headstock, a pulley mounted on each said shaft in keyed relation thereto and movable longitudinally 110 thereof, brackets carried by each headstock, said pulleys being secured to said respective brackets, means for reciprocating said headstocks longitudinally of said base, means for rotating said shafts from a common source 115 120 125 130

of power, and driving means associated with each said pulley and adjacent headstock whereby each grinding wheel spindle may be rotated in an orbital path about an axis eccentric to its own during the reciprocation of said headstocks.

5. In a grinding machine, in combination, a base, a work supporting table disposed substantially midway of said base and adjustable vertically and transversely, a pair of opposed headstocks mounted on said base and reciprocable longitudinally thereof, a grinding wheel spindle carried by each headstock and extending outwardly toward the opposed headstock, a motor carried by each headstock, means carried by said headstocks and associated with said motors for rotating said spindles about their own axes, a pair of shafts each extending longitudinally adjacent one of said headstocks, a bracket carried by and movable with each said headstock, a pulley mounted on and in keyed relation to and movable longitudinally of each said shaft and secured to said respective brackets, means 20 operatively associated with each said pulley and the respective headstocks to rotate said grinding wheel spindles in an orbital path about an axis eccentric to its own, a common driving means for rotating said shafts, 25 clutches disposed adjacent said shafts whereby said shafts may be rotated or disconnected at will, and speed changing mechanism associated with said common driving means whereby the rotative speed of said shafts may 30 be controlled.

6. In a grinding machine, in combination, an open-top base, a pair of oppositely disposed headstocks reciprocable on said base, a work supporting table supported substantially midway of said base, each headstock carrying a grinding wheel spindle extending toward the opposed headstock, independent means for rotating said grinding wheel spindles on their own axes, a longitudinally disposed rack carried by each headstock, shafts rotated from a common source of power, means for rotating said spindles in orbital paths about axes eccentric to their own from said respective shafts, pinions cooperatively 40 associated with said racks to reciprocate said headstocks, and means including reversing mechanism for transmitting power from said shafts to said respective headstocks, whereby said headstocks may be moved longitudinally in either direction.

7. In a grinding machine, an elongated base, a work support mounted on said base substantially midway between the ends thereof, a pair of opposed headstocks mounted on said base at opposite ends thereof and slideable longitudinally thereof, each headstock carrying a grinding wheel spindle which projects from the inner end thereof toward the opposed headstock, each spindle being mounted in its headstock for rotation about its own

axis and about an axis eccentric to its own, a motor carried by each headstock, means for driving the spindle of each headstock from the motor on the headstock in all positions of the spindle with respect to said eccentric axis, a mechanism for rotating each spindle about its eccentric axis, a mechanism for reciprocating each headstock on said base, and means driven from a common source of power for operating said mechanisms to simultaneously impart orbital and axial reciprocating movements to said spindles.

8. In a grinding machine, an elongated base, a work support mounted on said base substantially midway between the ends thereof, a pair of opposed headstocks mounted on said base at opposite ends thereof and slideable longitudinally thereof, each headstock carrying a grinding wheel spindle which projects from the inner end thereof toward the opposed headstock, each spindle being mounted in its headstock for rotation about its own axis and about an axis eccentric to its own, a motor carried by each headstock, means for driving the spindle of each headstock from the motor on the headstock in all positions of the spindle with respect to said eccentric axis, a mechanism for rotating each spindle about its eccentric axis, a mechanism for reciprocating each headstock on said base, and means including a change speed mechanism for simultaneously driving said mechanisms and for varying the angular speed of movement of each spindle about its eccentric axis and proportionately varying the speed of reciprocation thereof.

9. In a grinding machine, an elongated base, a work support mounted on said base substantially midway between the ends thereof, a pair of opposed headstocks mounted on said base at opposite ends thereof and slideable longitudinally thereof, each headstock carrying a grinding wheel spindle which projects from the inner end thereof toward the opposed headstock, each spindle being mounted in its headstock for rotation about its own axis and about an axis eccentric to its own, a motor carried by each headstock, means for driving the spindle of each headstock from the motor on the headstock in all positions of the spindle with respect to said eccentric axis, a mechanism for rotating each spindle about its eccentric axis, a mechanism for reciprocating each headstock on said base, a drive shaft, driving connections for simultaneously driving said mechanisms from said drive shaft, and a change speed mechanism interposed between said drive shaft and said mechanisms for varying the speeds thereof in relatively small increments throughout a relatively wide range of speeds.

In testimony whereof we affix our signatures.

HENRY H. YERK.

WILLIAM J. BAUMBERGER.
